UNITED STATES PATENT OFFICE.

ROLLO H. BEEBE, OF WATERLOO, IOWA.

AUTOMOBILE-JACK.

1,177,592.

Specification of Letters Patent.

Patented Apr. 4, 1916.

Application filed April 5, 1915. Serial No. 19,143.

To all whom it may concern:

Be it known that I, ROLLO H. BEEBE, a citizen of the United States of America, and a resident of Waterloo, Blackhawk county, Iowa, have invented certain new and Useful Improvements in Automobile-Jacks, of which the following is a specification.

My invention relates to improvements in lifting-jacks, and particularly to that type of jacks which is designed for use in lifting automobiles, and the object of my improvement is to provide actuating mechanism for the jack which, while operating the jack with an upward step-by-step movement will permit the lowering of the load with a controlled continuous movement. This object I have accomplished by the means which are hereinafter described and claimed, and which are illustrated in the accompanying drawings, in which:

Figure 1 is a side elevation of my improved lifting jack, with parts thereof sectioned away. Fig. 2 is an elevation of the opposite side of said jack, also showing parts sectioned or broken away.

Similar numerals of reference denote corresponding parts throughout the several views.

The numeral 5 denotes a vertical hollow standard integral with a circular base 6 and having a short vertical slot 8 near its upper end with a pair of horizontally projecting spaced vertical integral plates 9 of which only one is shown, the other being broken away. Within the hollow 7 of said standard is slidably seated a rack 1, having a rotatable curved or concave bearing block 2 rotatably mounted on its upper end by means of a screw pivot 3. The rack teeth 4 are alined in registration with the vertical slot 8 in the standard 5. A pinion 11 in mesh with the rack teeth 4, is fixedly mounted on a horizontal shaft 10, which latter is rotatably mounted in bearing openings in the brackets 9. One end of said shaft 10 extends outwardly beyond its bearing on that side and the relatively large disk or friction-wheel 26 is secured thereon by means of a key 31. A pawl 12 is pivoted on a stud 32 projecting from the inner face of one bracket 9 and is adapted to engage the teeth 4 on the rack 1. An arm mounted to swing up and down vertically within a loop 16 mounted on the inner face of one of the brackets 9 has its inner end bent to form

a part engaging the inner face of the pawl 12, while its other end has a bent over lip or finger piece 15. A small spring 17 is mounted on the stud 32 and is carried around the pawl 12 to exercise a yielding tension thereon to keep the pawl yieldingly engaged with the rack teeth 4. When the arm 14 is depressed the pawl 12 is moved away out of engagement with said rack.

Referring now to Fig. 2, the disk 26 has a circumferential edge channeled to provide spaced flanges 27. The circumferential rim of said wheel 26 is surrounded by means of a band brake composed of an elastic metal band 24 having a lining layer 25 composed of some highly frictional substance secured thereon to lie in contact with the rim. The ends of the band 24 are respectively pivotally secured on pintles 21 and 22 which are secured across the end bifurcations 20 of the socket 18, which contains the detachable handle bar 19. A coiled spring 29 is connected between hooks 30 and 28 mounted respectively on said socket 18 and on the band brake 24. A stop 23 on the bracket 9 restricts upward movement of the socket 18 and the handle bar 19. When the handle 19 is pushed downwardly, said band-brake is tightened about the friction wheel 26 and the latter with the shaft 10 and the pinion 11 is rotated to elevate the rack 1 with a step-by-step movement as the handle is moved alternately up and down. To lower the rack with a controlled continuous movement, the arm 14 is pushed down to release the pawl 12 from the teeth 4, and the handle 19 held in a position which will compress the band-brake sufficiently upon the wheel 26 to prevent the wheel from rotating too rapidly, and in this way the load may be gradually lowered without resorting to the delay and extra manipulation of step-by-step movements.

The strip or layer 25 which is mounted on the inner face of the band-brake 24 serves to add friction to the action of the brake, to more effectually control its action. When the arm 14 is released the spring 17 returns the pawl to engagement with the rack-teeth. The coiled spring 29 serves to keep the handle 19 in proper position for use, and the brake-band may be eased up or loosened about the wheel 26 by swinging the handle up against the stop-pin 23.

Various modifications in structure, dimensions, material or arrangement of the

parts of my device may be made, without, however, departing from the principles of or the scope of protection of my invention.

Having described my invention, what I claim as new, and desire to secure by Letters Patent, is:

1. A lifting-jack, comprising a rack mounted and supported for opposite movements, a pinion in mesh with said rack, a friction-disk adapted to rotate said pinion, a band-brake operatively mounted upon said disk to be frictionally engaged releasably therewith, means connected yieldingly to said band-brake to keep it under contact with said disk resiliently, a pivotally-mounted pawl releasably engaging said rack, and means for yieldingly resiliently retaining said pawl in engagement with said rack.
2. A lifting-jack, comprising a rack

mounted and supported for opposite movements, a pinion in mesh with said rack, a rotatable friction-disk adapted to rotate said pinion, a band-brake operatively engaged about said disk, a hand-lever having independent connections to the ends of said band-brake, a stop for limiting the movement of said lever in one direction, a yieldable resilient body connected to and adapted to exert a tension upon said lever when the latter is moved in one direction, a pawl releasably engaged with said rack, and means for releasing said pawl from said rack.

Signed at Waterloo, Iowa, this 22d day of March, 1915.

ROLLO H. BEEBE.
